UNITED STATES PATENT OFFICE.

BRONISŁAW GWÓŹDŹ, OF SCHÖNEICHE, NEAR BERLIN, GERMANY.

THERMIC TELEPHONE.

1,135,687.

Specification of Letters Patent. Patented Apr. 13, 1915.

Application filed September 14, 1911. Serial No. 649,388.

To all whom it may concern:

Be it known that I, BRONISŁAW Gwóźdź, a subject of the Czar of Russia, and residing at Schöneiche, near Berlin, Germany, have invented certain new and useful Improvements in Thermic Telephones, of which the following is a specification.

The subject-matter of my invention is an improved thermic telephone.

10 In the Letters Patent No. 998,965 is disclosed a process of manufacturing hot-wire devices for thermic telephones of platinum wires treated according to the Wollaston process, in which the shaped Wollaston 15 wire is provided with a cast, from one end of which projects only the portion of the wire to be subjected to the known corrosive process. The cast is block-like in shape, so that it can be used as a holder of the hot 20 wire in the telephone. This idea of using the cast as a holder of the hot wire admits of the hot wire being made readily exchangeable which is very important; particularly in thermic telephones.

25 Now a primary object of my invention is to provide a special construction of thermic telephone, comprising a hot-wire device which can be carried within the auditory duct. The telephone is very simple so that, 30 in spite of the smallness of the apparatus due to its purpose, the hot-wire device can be readily exchanged even by inexperienced persons. To these ends, the hot-wire device is connected in circuit within the telephone by means of an elastic frictional contact piece, so that it is only requisite to pull 35 out and push in the block-like hot-wire device in order to break or make the electrical connection when exchanging the device. In 40 addition, I employ in my new telephone for the exceedingly sensitive hot-wire an improved guard which positively protects the hot wire from contact with auditory secretions while the telephone is being used in

45 the ear and simultaneously allow the telephone to be cleaned in a simple manner without any difficulty to inexperienced persons and without any fear of the telephone being injured. The said guard forms a 50 double cover for the telephone aperture from which the sound issues, one cover being a tensioned porous very fine fabric, *e. g.* silk muslin, and the second a small perforated plate of solid material; the latter is arranged at a certain distance from the former and parallel thereto and can be removed

alone and independently of the said fabric from the telephone casing for the purpose of cleaning it.

One illustrative embodiment of my invention and several modifications thereof are represented by way of example on an enlarged scale in the accompanying drawing, wherein:

Figure 1 is a longitudinal section through one form of a thermic telephone in which the ends of the Wollaston wire are formed as contact pins; Fig. 2 is an elevation showing the principal parts of the apparatus according to Fig. 1 when pulled apart; Fig. 3 shows in sectional elevation and plan the principal parts of a modified form in which the Wollaston wires in the block-like cast open out into sockets adapted to receive contact pins; Fig. 4 is a bottom plan view of the telephone shown in Fig. 1; Fig. 5 is a longitudinal section through another modified form in which the block-like cast is provided with a metallic holder, and Figs. 6 and 7 show details of the telephone shown in Fig. 5; Figs. 8, 9 and 10 are detail views of a modified form of contact members.

Referring firstly to Figs. 1, 2 and 4, as is described in the Letters Patent No. 998,965, the Wollaston wire 1 is provided with a cast 2, from one end of which only the wire loop 3 serving as hot wire projects. The ends 4 of the Wollaston wire project from the other side of the block or cast 1 in such manner that they can be used as contact pins and be pushed into sockets 5 provided in a block-like body 6 composed of insulation. This insulator 6 and also the cast 2 are carried in a socket like casing 7 having a reduced end 8 through which the flexible cord 9 enters. This flexible cord 9 is prevented from being pulled out of the end 8 of the socket or casing 7 by a thickened portion or collar 10 which is provided at the end of the flexible cord and can be made in any suitable manner, *e. g.* by winding a silk or other thread around the cord, or by providing on the cord a special collar or cap as is represented in Fig. 5. The wires 11 of the flexible cord 9 have their ends inserted into the sockets 5 from the rear and may be soldered thereto for the sake of safety.

The insulator 6 and also the cast 2 are held in position in a screw-threaded cylinder 12 whose inner shoulder 13 rests against the front face of the cast 2. This cylinder 12 preferably has a conical aperture 14

forming the sound chamber in which is located the hot wire. Mounted on the front face 15 of the cylinder 12 is the above-mentioned, very fine, porous fabric 16 consisting, for example, of silk muslin or other similar material, which prevents the admission of foreign bodies into the sound chamber and to the hot wire, whereas the emission of the sound waves is not materially impaired.

10 Further, I arrange in front of the fabric 16 and parallel thereto a small perforated plate 17 which is preferably held in position by a ring 18 screwed on the cylinder 17 or is connected therewith, and can readily be removed alone or together with the ring 18 from the cylinder 12. Owing to the provision of this perforated plate the secretions in the ear will settle thereon and consequently cannot pass into the interior of the

20 sound chamber. But as this plate is composed of solid material, and consequently is not very sensitive or delicate and, in addition, is readily removable, after the same has been removed alone or together with the ring 18, it can be readily cleaned or washed, *e. g.* with alcohol, benzin or similar materials.

In order to exchange the hot-wire device in the embodiment according to Fig. 1 the cylindrical part 12 is first unscrewed and then the hot-wire device together with the insulator 6 carrying the sockets 5 are simply removed by pulling them out of the rear part of the casing 7 in the manner shown in Fig. 2. When this has been done the hot-wire device can be readily separated from the insulator 6. As described in my co-pending application Serial No. 644,243, filed Aug. 15, 1911, the new hot-wire device to be inserted is preferably provided with an elastic guard or cap 19 having a bell-shaped bottom 20 which protects the hot wire. The contact pins of the new hot-wire device provided with the cap 19 are then introduced into the sockets 5 of the insulator 6, whereupon both the cast 2 and the insulator 6 are pushed into the casing 7, this being readily possible because the hot wire of the cast 2 is protected by the cap 19. When the cast 2 is held in this manner in the casing 7 the cap 19 is removed by taking hold of its projecting edge with the finger-nails for example. The cylinder 12 together with the ring 18 are then screwed on in order to make the telephone apparatus ready for use.

The insulator 6 preferably has a recessed edge 21 or is provided with equivalent means, *e. g.* a groove, in order that a second hand can readily take hold of the cast 2 with the finger-nails when a hot-wire device is to be removed.

In the modification according to Fig. 3, the length of the cast 2 is diminished, this being preferable particularly in telephones to be introduced into the auditory duct;

within the cast 2 are embedded small tubes 22 into which the ends of the short Wollaston wire 1 project, and on the other hand, the wires 11 of the flexible cord 9 are connected with short slit tubes 23 formed as contact pins which are mounted by means of flanges 24 in a thin plate 25. The tube-like contact pins 23 only have to be pushed into the sockets 22 in the cast 2 in order to complete the circuit. The casing and other parts of the telephone may be formed as described above with reference to Fig. 1.

Fig. 5 shows another modified form. The block-like cast is here provided with a metal mount or holder 26 as is represented, for example, in Figs. 3, 7, 9 of my co-pending application Serial No. 644,243 filed Aug. 15, 1911, and in Fig. 11 of the same co-pending application, with which is connected the one end of the Wollaston wire. The other end of the Wollaston wire projects as an eye or loop 27 out of the cast. The position of the wire bow 3 serving as hot wire is the same as described above and in the Letters Patent mentioned above. In order to bring about the necessary electrical connection by simply pushing in the cast provided with the metal holder 26, the socket or casing 7 whose constricted part 8 likewise secures the thickened end or collar 10 of the flexible cable is provided within with a metal liner 28 which is held in the casing 7 by a screw 29, by which the one wire 11 is also secured in position. Further, within this slit, and therefore elastic, metal liner 28 is a loose insulator 30 which has at its end a recess 31 shown in Fig. 7 providing room for the head of the screw 29. The insulator 30 is hereby simultaneously prevented from rotating. At the opposite side the insulator 30 carries a screw 32 by which, on the one hand, the other wire 11 is held and which, on the other hand, holds a spring 33 which may either be bent U-shaped, as shown in Figs. 5 and 6, or may be of any other shape, *e. g.* spiral.

When the hot-wire device provided with the metal holder 26 and with a contact loop 27 is inserted into the casing 7 or into the elastic metal liner, the circuit is at once closed on the one hand by the one wire 11, the liner 28 and the holder 26, and on the other hand by the other wire 11, spring 33 and contact loop 27, so that the hot wire is fed with current and is exposed to the fluctuations of current in the circuit. The cast or the hot-wire device is secured in the telephone casing by means of a cylinder 12 as described above, and the fabric 16 and the small perforated plate 17 can also be employed, as shown in the drawing. The hot-wire device can in this form be exchanged more readily as compared with the examples according to Figs. 1 to 4 inasmuch as the hot-wire device does not require to be inserted in one special position in order to

connect it with the contact pins, because when the hot-wire device is simply pushed in in any position the required connection is brought about.

5 In order that it may be impossible to twist the flexible cord 9 in the end 8 of the socket or casing 7, as owing to the fineness of the wires this might readily lead to rupture of the wires 11, I prefer to provide the 10 end of the flexible cord with a metal collar or cap 10 having a lateral lug 34 projecting into a corresponding recess in the inner wall of the part 8, so that it is impossible for this cap and the flexible cord to turn inside 15 the casing.

In all the above-described embodiments, of which that shown in Fig. 5 is represented on a scale about twice the natural size, it is to be observed that constructive difficulties 20 are primarily due to the extreme smallness of the entire apparatus, and that the apparatus must be so formed that even an inexperienced person can readily exchange and clean its parts without injuring the exceedingly sensitive hot wire.

As emphasized above, the difficulty is to make such a thermic telephone so exceedingly small. For this reason there may be difficulty in the embodiment according to 30 Figs. 1 and 2 in arranging the conductors 11, on the one hand, and the ends of the Wollaston wire 4 formed as contact pins, on the other hand, in the insulator 6 inasmuch as owing to this insulator being very 35 thin there is not much room for securing the wires 11 in the requisite manner. Another object of my invention is to obviate this defect. To this end, I arrange the contacts in the insulator 6, as represented in Figs. 8 40 and 9. The contacts are here two small tubes *a* and *b* united in pairs by a small disk or bar *c*, as represented on an enlarged scale in Fig. 10. The tubes *a*, *b* pass completely through the insulator 6 and they are pref- 45 erably opposite one another, as shown in Fig. 8. The tubes *a* then serve for example for receiving the wires 11 of the flexible cord 9, while the ends 4 of the Wollaston wire formed as contact pins are inserted into 50 the tubes *b*. As the tubes *a*, *b* pass through the entire thickness of the insulator 6 as mentioned above, in this form there is a greater surface, so that greater safety is obtained both with regard to the arrangement 55 of the wires 11 and to the contact pins 4 to be held by friction.

It is obvious that the above-described contact member can be constructively modified in various respects. For example, for 60 each pole a small metal plate may be employed having two holes such that the wire 11 can be inserted into the one hole and the Wollaston wire formed as a contact pin into the other hole. Such constructive modi- 65 fications are likewise included in the scope

of the present invention, because it is solely a matter of providing for each pole two holes passing entirely through the insulator.

I claim:—

70 1. In a thermic telephone, the combination, with a casing, of contact means for connection to an electric circuit therein, an axially displaceable hot-wire device having contact members adapted to contact with the said contact means, and a body for holding the said hot-wire device in the contact position.

75 2. In a thermic telephone, the combination with a casing, of contact means for connection to an electric circuit therein, an axially displaceable hot-wire device having contact members adapted to contact with and be held in the casing by friction with said contact means and a member having a sound-chamber, secured detachably to the casing and holding the hot-wire device therein.

80 3. In a thermic telephone, the combination with a casing, of contact means for connection to an electric circuit therein, an axially displaceable hot-wire device, the ends of the said wire being connected to contact members adapted to contact with and be held in the casing by friction with the 85 said contact means and a member having a sound-chamber, secured detachably to the casing and holding the hot-wire device therein.

90 4. In a thermic telephone, the combination with a casing, of an axially displaceable hot-wire device therein, an insulator between the bottom of the casing and the hot-wire device, the said insulator being provided with contact means for connection to an electric circuit therein, the said hot-wire device being provided with contact members adapted to contact with and be held in the casing by friction with said contact means and a member having a sound-chamber, secured detachably to the casing and holding the hot-wire device therein.

100 5. In a thermic telephone, the combination with a casing, of an axially displaceable hot-wire device therein, an insulator between the bottom of the casing and the hot-wire device, the said insulator being provided with contact sockets connected with the conductors of the outer circuit, the said hot-wire device having projecting limbs adapted to engage the said sockets for connection to an electric circuit and a member having a sound-chamber, secured detachably to the casing and holding the hot-wire device therein.

105 6. In a thermic telephone, the combination with a casing having a male thread, of an insulator axially displaceable in the casing, two electrically conducting sockets carried by the insulator, a hot-wire device com- 110 120 125 130 135 140 145 150 155 160 165 170 175 180

prising a cast and a Wollaston wire carried thereby axially displaceable in the casing, the two limbs of the said Wollaston wire being normally held by friction by the said 5 sockets, and a cylindrical member screwed on the casing holding the said cast and the said insulator in the casing.

7. In a thermic telephone, the combination with a casing having a male thread, of 10 an insulator axially displaceable in the casing, two electrically conducting sockets carried by the insulator, a hot-wire device comprising a cast and a Wollaston wire carried thereby axially displaceable in the casing, 15 the two limbs of the said Wollaston wire being normally held by friction by the said sockets, and a cylindrical member having a sound chamber screwed on the casing holding the said cast and the said insulator in 20 the casing.

8. In a thermic telephone, the combination with a casing having a male thread, of 25 an insulator axially displaceable in the casing, two electrically conducting sockets carried by the insulator, a hot-wire device comprising a cast and a Wollaston wire carried thereby axially displaceable in the casing, the two limbs of the said Wollaston wire being normally held by friction by the said 30 sockets, and a cylindrical member having a

sound chamber screwed on the casing holding the said cast and the said insulator in the casing, a piece of fabric at one end of the sound chamber, a perforated plate or cap parallel to the piece of fabric, and a 35 ring mounted on the said cylindrical member securing the piece of fabric and the plate in position.

9. In a thermic telephone, the combination with a casing having a male thread, of 40 an insulator axially displaceable in the casing, two electrically conducting sockets carried by the insulator, a hot-wire device comprising a cast and a Wollaston wire carried thereby axially displaceable in the casing, 45 the two limbs of the said Wollaston wire being normally held by friction by the said sockets, a flexible cord passing through the bottom of the casing and connected to the said sockets, a collar on the end of the cord 50 in the casing, and a cylindrical member screwed on the casing, holding the said cast and the said insulator in the casing.

In testimony, that I claim the foregoing as my invention, I have signed my name in 55 presence of two subscribing witnesses.

BRONISŁAW GWOZDZ.
